UNITED STATES PATENT OFFICE.

GEORGE H. GILMAN, OF BOSTON, MASSACHUSETTS.

DRILLING MACHINE.

Application filed October 27, 1921. Serial No. 510,915.

To all whom it may concern:

Be it known that I, GEORGE H. GILMAN, a citizen of the United States, and a resident of Boston, county of Suffolk, State of Massachusetts, have invented an Improvement in Drilling Machines, of which the following description, in connection with the accompanying drawings, is a specification, like characters on the drawings representing like parts.

My invention relates to drilling machines and particularly but not exclusively to one for drilling rock.

My invention will be best understood from the following description when read in connection with the accompanying drawings of one specific embodiment of my invention selected for illustrative purposes while the scope of my invention will be more particularly pointed out in the appended claims.

In the drawings:—

Fig. 1 shows a longitudinal section of a portion of the drilling machine selected for illustrating my invention;

Figs. 2, 3, 4 and 5 respectively are sections on the lines 2—2, 3—3, 4—4 and 5—5 of Fig. 1.

Referring to the drawings of the embodiment selected for illustrating my invention, the drilling tool is represented by a drill steel 1. For imparting percussions to the tool I have provided a hammer piston 3 which in the present embodiment of my invention imparts a blow to the end of the

35 drill steel through the tappet 5.

I have shown the hammer piston mounted in the bore 6 of the cylinder section 7, which section is provided with an end wall 9 and with the alternate admission and exhaust

40 passages 11 and 13. These passages may be controlled by a suitable valve so as to alternately admit and exhaust pressure fluid to and from opposite sides of the hammer piston and thereby cause the latter to re-

45 ciprocate. The particular details of the mechanism for controlling the motive fluid for causing the hammer to reciprocate do not form a part of my present invention and will not be further described. It will

50 be understood that the motive fluid may be controlled or the hammer caused to reciprocate in any suitable manner, other than that just described.

Besides the cylinder section 7 I have 55 shown an intermediate section 15 which serves as a tappet block for the tappet 5

and have shown a forward section 17 which serves as a front head or chuck casing for the machine. These sections are held assembled by tie-bolts 19 which extend from the rear head block (not shown) of the machine through the cylinder section, the tappet block and chuck casing, the ends of the bolts exteriorly of the chuck casing carrying nuts 21 which engage the shoulders 23 formed on the chuck casing and surrounding the bolt holes.

For carrying the drill steel I provide a chuck which as illustrated comprises an outer sleeve member 25 and inner sleeve 70 member 27, the latter of which interiorly is of polygonal cross section and receives the polygonal shank of the drill steel. The outer member at its forward end is provided with diametrically oppositely located 75 slots 29 which receive the similarly located radially extending lugs 31 carried by the inner sleeve. When the parts are assembled the lugs 31 enter the recesses 29 which causes the sleeves to be interlocked against relative 80 angular movement.

Near its rearward end the outer chuck sleeve member 25 is illustrated as provided with an annular series of exterior gear teeth 33. These gear teeth are adapted to cooperate with gearing for driving the chuck in order that the drill steel may be rotated. In the submitted embodiment I have shown for this purpose a yoke 35 provided with the annular series of internal gear teeth 37 90 for meshing with the gear teeth 33. This yoke is adapted to be gyrated by means of the eccentrics 39 which are carried by the shafts 41. The shafts may be driven by any suitable means, as for example, by a rotary engine (not shown) connected with the shafts in any suitable manner. At their forward ends the shafts are journaled in bearing recesses 42 formed in the chuck casing.

100 Adjacent the tappet block the chuck casing is enlarged to form a gear chamber 43. To provide this chamber the chuck casing is formed with a rearward axially located cylindrical bore 45 and intersecting this bore 105 formed with oppositely located cylindrical bores 47. The tappet block is provided with an axial cylindrical boss 49 which enters and fits the bore 45 and further is provided with flanges 51 which extend across the bores 45. 110 In the tappet block are formed cylindrical bores 53 of the same diameter as and in

alignment with the bores 47, a portion of the bores 53 being formed in the flanges and the remainder thereof in the cylindrical boss 49.

5 Supporting the shafts 41 are cylindrical bearing blocks 55 which enter the bores 47 and 53 and further are received in the cylindrical bores 57 in the forward face of the end wall of the cylinder. It will be noted 10 by this construction that the bearing blocks 55 serve as dowels which align the cylinder, the tappet block and the chuck casing and prevent relative rotation between these parts. For holding the bearing blocks 15 against movement I provide keys 58 received in key-ways 59 and 60 respectively formed in the bearing blocks and the flanges 51 while the end of the keys abuts the end of the chuck casing which holds the keys in 20 position. At its rearward side the tappet is provided with the cylindrical boss 61 which is received in the bore 62 in the end wall 9 of the cylinder section and this insures centering of the tappet with the piston and 25 steel.

Forwardly of the gear portion 33 the chuck sleeve 25 has a bearing in the chuck casing, while rearwardly of the gear portion the sleeve has a bearing 63 in the tappet 30 block. It will be noted by this construction the gear chamber 43 is isolated from the interior of the chuck by means of the bearings and that this prevents sludge or water from working into said gear chamber. For draining 35 the chuck of sludge or water and particularly when the machine is used for drilling up-holes as when my invention is applied to a stoper I provide passages 67 formed in the cylinder section and in the tappet block 40 and which place the interior of the chuck casing between the forward end of the tappet and the rearward end of the sleeve 25 in communication with the atmosphere. The water just referred to is fed in my present 45 embodiment to the drill steel through a tube 68, one end of the tube being mounted at the rear of the machine and the tube passing through the piston and tappet and terminating inside the bore of the hollow steel.

50 It is of advantage to at times prevent rotation of the chuck relatively to its casing, especially in machines in which the hole is spotted by bodily rotating the machine by hand, as for example, in a stoper. For this 55 purpose and for the purpose of providing a brake for opposing rotation of the chuck under the influence of the power means, I provide friction means cooperating with the chuck, and herein to this end I have shown 60 the chuck casing provided with a semi-annular recess 69 which receives a band 71 surrounding the chuck and adapted to be forced into engagement with the exterior surface of the sleeve 25. The band may be of flexible material, preferably metal, as for ex-

ample a split spring ring of internal diameter greater than the exterior diameter of the chuck so that when the ring is spread as shown by Fig. 4 it will substantially be out of engagement with the chuck. For operating the band I herein provide its ends with opposed nuts 73, one nut engaging the screw-threaded portion 75 of the member 77 and the other the oppositely pitched screw-threaded portion 79 of the member 81. The member 81 is in the form of a spindle provided with a reduced diameter portion 83, and on which is carried the member 77, the latter being in the form of a sleeve. For operating the right and left hand bolt thus 80 formed I provide a handle 85 and for keying the handle to the members and the members to each other I provide the cotter-pin 85 87.

As best shown in Figs. 1 and 4, the chuck casing in the present embodiment of my invention is provided with an enlargement 89 which receives the nuts 73 and the members 77 and 81. The member 81 as illustrated by Fig. 4 has a bearing in an opening in one side wall of the enlargement, while the member 77 has a bearing in an opening in the opposite side wall of the enlargement. Externally of the casing the member 81 carries a head 84 secured to the bolt by means of a pin 85 while the handle abuts the opposite side of the enlargement and in this manner longitudinal movement of the members is prevented. It will be noticed by this construction the parts may be readily assembled, while retaining an integral construction for the chuck casing. 90

This application claims an improvement of the invention for which applicant has filed copending application Serial No. 105 407,773, filed September 2, 1920.

Although I have described for purposes of illustration one specific embodiment of my invention it will be understood that I am not limited thereby to its particular details but that wide deviations may be made therefrom without departing from the spirit of my invention. 110

Claims:

1. In a drilling machine, a front head, a chuck rotatably carried by said front head, means for rotating said chuck relatively to said front head, and releasable friction means controlled by the operator for preventing rotation of said chuck relatively to said head. 115

2. In a drilling machine, a chuck, power means for rotating said chuck, a friction brake for opposing rotation of said chuck, and manually controlled means for rendering said brake operative or inoperative. 125

3. In a drilling machine, a drilling tool, an angularly moving part for imparting angular movement to said tool, friction means for opposing movement of said part, 130

and manually controlled means for rendering said friction means operative or inoperative.

4. In a drilling machine, a chuck, a casing for said chuck, a band encircling said chuck, and manually operated means carried by said casing for operating said band to cause it to grip or release said chuck.

5. In a drilling machine, a drill steel, a chuck comprising a sleeve for carrying said steel, a second sleeve surrounding the sleeve first mentioned and interlocked therewith, power means in driving relation with said sleeve first mentioned for rotating said chuck, means for engaging one of said sleeves for preventing rotation of said chuck, and manually controlled means for rendering said means engaging one of said sleeves operative or inoperative.

6. In a drilling machine, a drill steel, a chuck comprising an inner and an outer sleeve, said sleeves being interlocked against relative rotation, said inner sleeve nonrotatably carrying said steel, power means for driving said chuck and connected to said outer sleeve, and manually controlled means for preventing rotation of said steel and adapted to engage said outer sleeve.

7. In a drilling machine, a drill steel, a hammer piston for operating said steel, a chuck carrying said steel, a chuck casing in which said chuck is rotatably mounted, a band encircling said chuck, an operating handle carried by said casing, and means operated by said handle for constricting said band to cause it to grip said chuck and thereby prevent rotation of said chuck relatively to its casing.

8. In a drilling machine, a drill steel, a hammer piston for operating said steel, a chuck carrying said steel, a chuck casing in which said chuck is rotatably mounted,

means including a band encircling said chuck for frictionally gripping said chuck to prevent rotation of said chuck relatively to said casing, and means including an operating handle carried by said casing for actuating said band for rendering it operative or inoperative.

9. In a drilling machine, a drill steel, a hammer piston for operating said steel, a chuck carrying said steel, a chuck casing in which said chuck is rotatably mounted, means including a band encircling said chuck for frictionally gripping said chuck to prevent rotation of said chuck relatively to said casing, and means including a screw and an operating handle carried by said casing for actuating said band for rendering it operative or inoperative.

10. In a drilling machine, a drill steel, a hammer piston for operating said steel, a chuck carrying said steel, a chuck casing in which said chuck is rotatably mounted, means including a band encircling said chuck for frictionally gripping said chuck to prevent rotation of said chuck relatively to said casing, and means including a cam and an operating handle carried by said casing for actuating said band for rendering it operative or inoperative.

11. In a drilling machine, a drill steel, a hammer piston for operating said steel, a chuck carrying said steel, a chuck casing in which said chuck is rotatably mounted, friction means carried by said casing for yieldingly gripping said chuck to prevent rotation thereof, and an operating handle carried by said casing for rendering said friction means operative or inoperative.

In testimony whereof, I have signed my name to this specification.

GEORGE H. GILMAN.
